US0D1108622S

(12) **United States Design Patent** (10) Patent No.: **US D1,108,622 S**
(45) Date of Patent: ** Jan. 6, 2026

(54) **CIRCUIT KIT FOR A HUMIDIFIER**

(71) Applicant: **Fisher & Paykel Healthcare Limited**,
Auckland (NZ)

(72) Inventors: **Thomas Jacques Fernand Maeckelberghe**, Auckland (NZ);
Gareth James Hobbs, Auckland (NZ);
Matthew Liam Buswell, Auckland (NZ);
Jason Allan Klenner, Auckland (NZ);
David Leon McCauley,
Auckland (NZ); **Elmo Benson Stoks**,
Auckland (NZ); **Samuel Graham Boggs**, Auckland (NZ); **Jonathan Andrew George Lambert**, Auckland (NZ); **James William Stanton**,
Auckland (NZ)

(73) Assignee: **Fisher & Paykel Healthcare Limited**,
Auckland (NZ)

(**) Term: **15 Years**

(21) Appl. No.: **29/915,008**

(22) Filed: **Oct. 24, 2023**

CLAIM

The ornamental design for a circuit kit for a humidifier as shown and described.

DESCRIPTION

FIG. 1 is a top, front and side perspective view of a circuit kit for a humidifier showing a chamber embodying our new design;

FIG. 2 is a top, rear and side perspective view thereof;

FIG. 3 is a front view thereof;

FIG. 4 is a rear view thereof;

FIG. 5 is a first side view thereof;

FIG. 6 is a second side view thereof; and,

FIG. 7 is a top view thereof.
